(57) **CLAIM**

The ornamental design for a bed, as shown and described.

DESCRIPTION

FIG. 1 is a right side, elevational view of the design of a bed according to the present invention, with the left side being the mirror image thereof;

FIG. 2 is a front, elevational view of the bed shown in FIG. 1, with the rear view being the mirror image thereof;

FIG. 3 is a left side, bottom perspective view of the bed shown in FIG. 1;

FIG. 4 is a right side, top perspective view of the bed shown in FIG. 1;

FIG. 5 is a right side, elevational view of the bed shown in FIG. 1, set in an alternative position;

FIG. 6 is a left side, bottom perspective view of the bed shown in FIG. 1 set in the position shown in FIG. 5;

FIG. 7 is a right side, top perspective view of the bed shown in FIG. 1 set in the position shown in FIG. 5;

FIG. 8 is a right side, bottom perspective view of the bed shown in FIG. 1, set in yet another alternative position; and,

FIG. 9 is a right side, top perspective view of the bed shown in FIG. 1 set in the position shown in FIG. 8.
